UNITED STATES PATENT OFFICE

ALBERT C. SCHLEH, OF ST. PAUL, MINNESOTA

ECONOMIZER

Application filed January 27, 1928. Serial No. 249,868.

My invention relates to economizers and particularly to devices of this nature adapted to be installed in the smoke pipe of boilers, furnaces or other heating plants for utilizing of heat ordinarily lost in the exhaust gases of said heating plants, and has for its object to provide a device whereby the heat ordinarily wasted in the exhaust gases of such heating plants may be utilized for useful purposes without appreciably affecting the draft in the heating plant.

An object of the invention resides in providing an elongated casing having upper and lower partitions therein spaced from the top and bottom of said casing to form upper and lower compartments and in inter-connecting said upper and lower partitions with a series of circular flues arranged in a row in said casing and communicating with said upper and lower compartments and in providing said upper and lower compartments with a warm air outlet and a cold air inlet respectively.

Another object resides in surrounding said flues with a jacket extending from the upper partition to within a short distance of the lower partition and following the curvature of said flues to form a tortuous passageway extending around the same and to further provide an exhaust gas inlet and an exhaust gas outlet communicating with said passageway adapted to be inserted in the smoke pipe for conducting the exhaust gases from the furnace or heating plant through the economizer.

A feature of the invention resides in spacing the two central flues and inserting therebetween a vertical wall and in further arranging the exhaust gas inlet and outlet near the upper partition of said casing on opposite sides of said wall and in constructing said wall with a valve adapted to conduct the exhaust gases directly from said exhaust gas inlet to said outlet through said wall.

Other objects of the invention will be found in the detailed description of the same and in the claims forming a part of this specification.

In the drawings illustrating my invention in one form:

Fig. 1 is a plan sectional view taken

through the center of the exhaust gas inlet and outlet.

Fig. 2 is an elevational sectional view taken on line 2—2 of Fig. 1.

Fig. 3 is a vertical sectional view taken on line 3—3 of Fig. 1.

In ordinary residential heating plants an appreciable quantity of heat is lost due to the temperature of the exhaust gases from the heating plant in leaving the same. My invention provides a simple and effective means whereby this excess temperature may be utilized to heat the interior of the building so that when the exhaust gases are finally expelled into the chimney the same are at a relatively low temperature.

My invention proper consists of a casing A formed with side walls 10 and 11 and end walls 12 and 13. These walls are connected by means of a hopper-shaped top 14 and a hopper shaped bottom 15. Within the casing is disposed an upper partition 16 and a lower partition 17 which are spaced from the top 14 and bottom 15 to form upper and lower compartments 18 and 19. Between these partitions are arranged a row of circular flues 20, 21, 22, 23, 24 and 25, which flues interconnect said partitions 16 and 17 and communicate with the compartments 18 and 19. Within each of these flues is arranged a number of radial inwardly extending fins 20 which are preferably constructed of copper or some other suitable heat conducting material and which aid in conducting heat from the exterior of said flues to the air passing upwardly through the same.

At the lower end of the casing A is provided an air inlet 121 to which the cold air pipe 122 may be attached, which is adapted to conduct cold air into the lower compartment 19. Immediately above this inlet is provided a baffle or deflector 231 supported on legs 123 which serves to distribute the incoming cold air so that the same passes equally through the various flues 20, 21, 22, 23, 24 and 25. At the upper end of the casing A is disposed a warm air outlet 124 which has connected to it a warm air pipe 125. This outlet communicates with the compartment 18 and serves to conduct away the air heated by the economizer.

An inspection of Fig. 1 shows that the flues 22 and 23 are relatively spaced from one another while the remaining flues are relatively close to one another, and that the flues are arranged in a single row in substantial alignment. Between the two flues 22 and 23 is arranged a vertical wall 26 which extends from one flue to the other and reaches from the partition 16 to the partition 17. Strips of metal 27 are connected between the remaining flues and extend from the partition 16 to within a short distance of the lower partition 17 and serve the same purpose as the wall 26. By means of these strips of metal, partition 26 and the various flues the interior of the case A is substantially divided in two parts. Within casing A is arranged a jacket 28 which surrounds the various flues 20 to 25 and is spaced therefrom and follows the curvature of said flues to provide a narrow tortuous passageway 29 extending completely about the same. This jacket extends up to the upper partition 16 but falls short of the lower partition 17, leaving an open space 30 bringing said passageway or chamber into communication with the interior of the casing A. At the uppermost portion thereof the jacket 28 is connected on opposite sides of the wall 26 with an exhaust gas inlet 31 and an exhaust gas outlet 32 which pass through the two walls 10 and 11 of said casing. The inlet and outlet are adapted to be connected to pipes 33 and 34 which form a portion of the smoke pipe of the furnace or other heating plant with which the invention is installed. The inlet 31 communicates with the passageway 29 so that the exhaust gas from the heating plant upon entering said inlet strikes the wall 26 and divides passing equally to the right and left through the passageway 29 and unites on the opposite side of said wall, leaving the device through the outlet 32. During such passage through the economizer the heat in the exhaust gas is absorbed by the walls of the flues 20 to 25 and conducted to the air passing through the interior of the same. It is to be noted that during the passage of the exhaust gases through the economizer that the same does not change its elevation so that the draft of the heating plant remains practically unaffected, while the waste heat in the exhaust gases may be readily made use of. In the construction of the jacket 28 the same may be brought toward the walls 10 and 11 as shown in Fig. 1 and the inlet and outlet 31 and 32 formed directly in said walls 10 and 11. With this construction the exhaust gas most easily enters the passageway 29 due to the curvature of the said jacket indicated at 35. If desired, however, the said jacket may be extended tangentially across the two flues 22 and 23, and the inlet 31 and outlet 32 connected directly through the same. In either event the construction provides two

chambers 36 and 37 with which the inlet 31 and outlet 32 communicate.

In the wall 26 is arranged an opening 38 which is in substantial alignment with inlet 31 and outlet 32. This opening is normally closed by means of a closure 39 disposed within chamber 37 and hingedly connected to said wall 26 as indicated at 40. A counter-weight 41 attached to the lower portion of this closure serves to hold the same in a position to normally close the opening 38. This closure serves as a relief valve in the event that the pressure within the chamber 36 becomes too great. In such event the pressure within said chamber lifts the closure 39 from closing position allowing the gas to escape through the wall 26 and directly into the outlet 32. In the event that the amount of gas generated by the heating plant is too great to be comfortably handled by the passageway 29, said passageway being open as indicated by 30 permits the excess portion of the exhaust gas to escape into the interior of casing A where the same may bypass said passageway and enter the exhaust chamber 37 and be removed from the economizer. In this manner my economizer will function equally as well whether installed on small or large heating plants within suitable limits and will function equally as well with any kind of fuel.

For the purpose of cleaning the interior of the casing A I arrange two hand holes 42 and 43 at the lower portion of the end wall 12 of said casing A by means of which a brush may be inserted into the same for removing the soot or other deposit accumulating therein. These hand holes may be closed by suitable covers 44 so that when the device is in operation the casing is completely sealed from the exterior. If desired, the entire casing may be completely covered with insulation, or the heat given off by the surface of the casing may be utilized to heat the room in which the economizer is installed.

In the installation of the device, if desired, the cold air pipe 122 may be connected to the exterior of the building so that fresh air may be taken into the building and discharged wherever desired. If further economy is preferable the pipe 22 may be connected with one or more of the registers in the rooms of the building to be heated or the heat utilized for any other desired purpose.

My invention is highly advantageous in that it provides a simple and effective device for utilizing the waste heat ordinarily expelled with the exhaust gases of a heating plant. The device so functions as to offer a minimum resistance to the passage of the air to be heated and to the exhaust gases, thereby giving a maximum capacity and practically having no effect upon the draft of the heating plant. The device is fully automatic taking care of excess exhaust gases as well as unusual pressure occurring in the

smoke pipe. The device may be readily cleaned and there are no complicated or intricate parts to get out of order in the operation of the same. The economizer may be constructed almost entirely of sheet iron so that the same may be built at a nominal cost.

Changes in the specific form of my invention, as herein disclosed, may be made within the scope of what is claimed without departing from the spirit of my invention.

Having described my invention, what I claim as new and desire to protect by Letters Patent is:

1. An economizer comprising a casing, spaced partitions at the upper and lower portion of said casing forming upper and lower compartments, a series of flues interconnecting said partitions and communicating with said compartments, a cold air inlet communicating with said lower compartment, a warm air outlet communicating with said upper compartment, a jacket surrounding said flues and spaced therefrom and forming a passageway thereabout, an inlet to said passageway, an outlet to said passageway, said jacket extending up to the upper partitions to form said passageway closed at the upper end, said jacket being spaced from the lower partition to form said passageway open at its lower end to permit of bypassing a portion of the exhaust gas from said passageway.

2. An economizer comprising a casing, spaced partitions at the upper and lower portion of said casing forming upper and lower compartments, a series of flues interconnecting said partitions and communicating with said compartments, a cold air inlet communicating with said lower compartment, a warm air outlet communicating with said upper compartment, two of said flues being spaced from one another, a vertical wall connecting said flues, a jacket surrounding said flues on both sides thereof and disposed within said casing and forming a passageway thereabout, an exhaust gas inlet communicating with said passageway on one side of said wall and an exhaust gas outlet communicating with said passageway on the other side of said wall and substantially opposite to said inlet and a valve disposed within said wall for permitting exhaust gases to flow through said passageway or directly through said wall from said inlet to said outlet.

3. An economizer comprising a casing, spaced partitions at the upper and lower portion of said casing forming upper and lower compartments, a series of flues interconnecting said partitions and communicating with said compartments, a cold air inlet communicating with said lower compartment, a warm air outlet communicating with said upper compartment, a jacket surrounding said flues and spaced therefrom and forming

a passageway thereabout, an inlet to said passageway for conducting exhaust gases thereto, an outlet to said passageway for removing the exhaust gases therefrom, said jacket extending up to the upper partitions to form 70 said passageway closed at the upper end and being spaced from the lower partition to form said passageway open at its lower end to permit of bypassing a portion of the exhaust gas around said passageway, said exhaust gas inlet and outlet being disposed near the upper portion of said passageway.

4. An economizer comprising an elongated casing, spaced partitions at the upper and lower portion thereof forming upper and lower compartments within said casing, a row of circular flues interconnecting said partitions and communicating with said upper and lower compartments, an air inlet connected with said lower compartment, an air outlet connected with said upper compartment, the two flues at the center being spaced apart, a wall positioned between said flues and partitions, a jacket surrounding said flues and spaced therefrom and conforming to the curvature of said flues to form a circuitous passageway extending about said flues, said jacket extending up to said upper partition and being spaced from said lower partition to permit of the escape of surplus 95 exhaust gases from said passageway and an inlet and outlet to said passageway for conducting exhaust gases thereto and therefrom.

5. An economizer comprising a casing, a series of upwardly extending conduits within said casing for conducting the fluid to be heated through said casing, and a jacket surrounding said conduits and forming in conjunction therewith a continuous passageway substantially horizontal throughout its extent for conducting the heating fluid about said conduits.

6. An economizer comprising a casing, a series of upwardly extending conduits within said casing for conducting the fluid to be heated through said casing, means forming in conjunction with said conduits a circuitous passageway for conducting the heating fluid about said conduits, an inlet to said passageway and an outlet therefor, said inlet and outlet being positioned in close proximity to one another, and a valve between said inlet and outlet.

7. An economizer comprising a casing, a series of upwardly extending conduits within said casing for conducting the fluid to be heated through said casing, means forming in conjunction with said conduits a circuitous passageway for conducting the heating fluid about said conduits, an inlet to said passageway, an outlet therefor, and a valve in said passageway situated near said inlet and discharging into said outlet.

8. An economizer comprising a casing, a series of upwardly extending conduits within 130

- said casing for conducting the fluid to be heated through said casing, means forming in conjunction with said conduits a circuitous passageway for conducting the heating fluid about said conduits, an inlet to said passageway, an outlet therefor, said inlet and outlet being in substantial alignment, and a relief valve for said passageway situated between said inlet and outlet and in substantial alignment therewith.
9. An economizer comprising a casing, a series of upwardly extending conduits within said casing for conducting the fluid to be heated through said casing, means forming a chamber about said conduits, a jacket disposed within said chamber and forming in conjunction with said conduits a passageway for conducting the heating fluid about said conduits, said passageway communicating with said chamber.
10. An economizer comprising a casing, a series of upwardly extending conduits within said casing for conducting the fluid to be heated through said casing, a jacket surrounding said conduits and forming in conjunction therewith a tortuous passageway for conducting the heating fluid about said conduits, and means forming a free passageway for the heating fluid coextensive with said tortuous passageway, said passageways being in communication.
11. An economizer comprising a casing, a series of upwardly extending conduits within said casing for conducting the fluid to be heated through said casing, a jacket surrounding said conduits and forming in conjunction therewith a tortuous passageway for conducting the heating fluid about said conduits, and means forming a free passageway for the heating fluid coextensive with said tortuous passageway, said passageways being in communication throughout their extent.
12. An economizer comprising a casing, a series of upwardly extending flues within said casing for conducting the fluid to be heated through said casing, two of said flues being spaced from one another, a jacket surrounding said casing and forming in conjunction therewith a passageway for conducting the heated fluid about said flues, a wall positioned between said spaced flues, an inlet pipe communicating with said passageway on one side of said wall, an outlet pipe communicating with said passageway on the other side of said wall, said wall having an opening therein adapted to bring said outlet into communication with said inlet, a closure for said opening hingedly connected to said wall at the upper portion thereof, and means for yieldingly supporting said closure in closing position.

In testimony whereof I have affixed my signature to this specification.
